UNITED STATES PATENT OFFICE.

SIGMUND L. LEDERER, OF PROVIDENCE, RHODE ISLAND, ASSIGNOR TO PROVIDENCE STOCK COMPANY, OF PROVIDENCE, RHODE ISLAND.

END HOOK.

Application filed May 19, 1926. Serial No. 110,179.

This invention relates to certain new and useful improvements in end hooks and pertains more especially to end hooks for bracelets.

5 The primary object of the invention is to provide an improved structure of end hook which is of simple, economical and compact construction and which can be easily and quickly assembled and without the 10 use of solder.

A further object of the invention is to provide a hook of this type which can be snapped onto or over the usual bar on the watch and which can be easily and quickly 15 operated to release the hook.

A still further object of the invention is to provide a structure wherein accidental disengagement of the parts is minimized.

In the drawings:

20 Fig. 1 is a top plan view of the invention.

Fig. 2 is a bottom plan view of the invention.

25 Fig. 3 is a section on line 3—3 of Fig. 1, and

Fig. 4 is a perspective view of the spring.

In proceeding in accordance with the present invention 1 indicates the hook which is centrally slotted at 2, thereby affording 30 a bifurcated hook. The shank 3 of the hook may be soldered to the bracelet B or other part, to which the hook is to be connected. Preferably the shank has lips 3' on its sides which are bent or curled over the bracelet 35 sides, as shown, thereby to afford a firm and positive connection.

A pin 4 extends through ears 5 on the sides of shank 3 and also through ears 6 on the inner end of a substantially Z shaped 40 latch 7. The outer end of the latch is reduced in width to be received in the slot 2 of the hook and is curved at 8 to conform to the watch bar (not shown) and has its end 9 bent outwardly at an angle to form 45 a finger nail grip.

It also will be evident that by reason of the slots 7' formed at the back of the latch 7 when the latch 7 is lifted its full movement it will be locked in the raised position by reason of the sides of the latch 7 50 contacting with the sides of the slot 2.

A substantially V-shaped spring 10 is employed to tension the latch and bears at one end against the latch and at its other 55 end against the shank 3. The spring is

preferably slotted at 11 to improve its resiliency and receives the pin 4 in its angle, thereby preventing forward movement of the spring, rearward movement being prevented by contact with the bracelet end B 60 or other part to which the shank 3 is connected.

From the foregoing it will be seen that in applying the hook it is merely necessary to effect relative engagement of the latch and 65 the watch bar so as to cause the latch to move inward whereupon the bar will be engaged in the hook and between the latter and the part 8 of the latch. To disengage the parts it is merely necessary to 70 grip end 8 of the latch and to move the same to release the latch.

Since the part 8 lies directly opposite to the hook it will be noted that accidental disengagement is minimized, since an angular 75 movement of the latch is required to release the same.

Having thus described my invention, what I claim as new and desire to secure by Letters Patent is:

1. In combination with a hook having a shank, the hook being centrally slotted, a substantially Z-shaped latch, a pin carried by the shank and to which the latch is pivoted at one end, the other end of the latch being 85 reduced in width to be received in the slot of the hook and having a curved part directly opposed to the hook and an angular outwardly extending finger-engaging end, a substantially V-shaped spring centrally slotted and engaged between the shank and the first 90 named end of the latch and receiving the pin in its angle, and means to connect an object to the shank so that the object lies adjacent to the angular end of the spring and holds the latter onto the pin.

2. In combination with a hook having a slot which extends through the free end thereof and a shank, a substantially Z-shaped latch pivoted to the shank and having a reduced curved part received in the slot and having an end formed to provide a finger grip which latter is normally disposed below the top of the hook, and spring means 100 to tension the latch.

3. In combination with a hook having a shank, a latch for closing the mouth of the hook, a pin carried by the shank and to which the latch is pivoted, a substantially V-shaped spring for tensioning the latch and 110

receiving the pin in its angle, and means to connect an object to the shank so that the object lies adjacent to the angular end of the spring and holds the latter onto the pin.

5. 4. In combination with a bifurcated hook, a latch composed of a plate pivoted at its rear end to the hook and having its front end curved from a point adjacent the free end of the hook rearwardly of the latter and then 19 toward the hook so as to dispose the free end of the curved part of the latch between the furcations of the hook, and spring means to tension the latch.

5. In combination with a bifurcated hook, 15 a latch, having a free end formed with ta-

pering sides which are engageable with the furcations of the hook to hold the latch in open position, and means to tension the latch.

6. In combination with a bifurcated hook, 20 a latch having sides engageable with the inner sides of the furcations of the hook, the sides of one of the latter two elements being inclined whereby to cause the latch when open to be held against closing, and means 25 to tension the hook.

In testimony whereof I have signed my name to this specification.

SIGMUND I. LEDERER.
